THERMOSTATICALLY CONTROLLED
ASH TRAY

Morris Kenes, Stratford, Conn.

Application April 17, 1950, Serial No. 156,362

12 Claims. (Cl. 131—240)

1

This invention relates to smokers' ash trays, and has for an object to provide an ash tray which has a safety device to prevent a lighted cigarette or the like from dropping onto a table-cloth, finished table top or other support on which the tray may be used, and thus preventing burning or marring of such cloth or surface. Ash trays have been made in which a thermostat is used to tip the cigarette rest mounted in the tray when a cigarette resting in this rest burns to a certain point, but as in this device the thermostat is used as the operating means to tip the rest, considerable movement is required of the thermostat, which requires considerable heating. The result is that after the rest has been tipped to discharge the cigarette into the tray considerable time is required for the thermostat to cool sufficiently to return the rest to the normal position. Also the thermostat may not be heated sufficiently to cause the necessary tipping of the rest to deposit the lighted cigarette in the tray.

It is therefore another object of the present device to provide a rest for the lighted cigarette which is overbalanced and on which a control thermostat is mounted, which thermostat acts only as a catch means for holding the rest in the normal position, and is so arranged that only a slight movement of the thermostat is required to release the rest to permit it to tip to discharge the lighted cigarette into the tray, and therefore only a relatively small heating of the thermostat is required to release the rest and as a result the thermostat acts very rapidly to permit tipping of the rest and after operation the thermostat cools very rapidly, so that it returns almost immediately to the holding position, and therefore the rest can be returned immediately and reset in its normal holding position.

It is a further object of the invention to provide a structure of this type which is of very simple construction and can be manufactured at low cost.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of the cigarette rest and a portion of the ash tray on which it is mounted, with parts broken away to more clearly show the construction;

2

Fig. 2 is a section substantially on line 2—2 of Fig. 1;

Fig. 3 is a section substantially on line 3—3 of Fig. 1;

Fig. 4 is a section on substantially the same line but showing the rest in the tipped position;

Fig. 5 is an end view looking from the right of Fig. 1, and

Fig. 6 is a development of the bracket used for mounting the rest.

The device comprises an ash tray 10 of any suitable construction, but preferably dished to form a receptacle for the ashes with a rim 11, and it may be of any form or shape. Secured to the rim 11 on one side is a cigarette rest or holder, indicated as a whole at 12, and there may be one or more secured to the rim of the tray as found desirable. This holder comprises a supporting bracket 13 including a pair of laterally spaced upright side plates 14 connected at their outer ends by the transverse wall 15 in which is an upright slot or opening 16. At the lower edge of the wall 15 is an outwardly extending lug or ear 17 which may be soldered or welded to the top of the flange 11, as indicated at 18, to mount this holder on the tray. It will be seen that with this arrangement the side walls 14 extend inwardly over the tray 10. Pivoted between these side walls 14 is a transversely curved holder or rest 19 for a cigarette, cigar or similar article indicated at dotted lines at 20, and this rest is pivoted to the side members 14 by a transverse pin 21 secured to the under side of the rest and projecting at its opposite ends into openings 22 in the side walls 14. This pivot support for the rest 19 is located adjacent the outer end of this rest so that it is overbalanced on the inside from this pivot and therefore its inner end over the tray tends to tip or drop by force of gravity to an inclined position as shown by Fig. 4.

Secured adjacent the inner end of this concave or trough-shaped rest 19 is a bimetal thermostat 23. It is preferably shaped substantially as indicated in Fig. 1, with its end 24 secured to the under side of the member 19 by soldering or other suitable means, and then it is curved laterally and backwardly, as indicated at 25, this curved portion being located inwardly and spaced somewhat from the inner end 26 of the member 19, which end is also preferably concavely curved, as shown in Fig. 1. The other side 27 of the thermostat extends backwardly toward the rim of the tray and in normal position its free end 28 is located just outwardly of one edge of the opening 16, as shown in Figs. 1, 3 and 5, so that this end rests against the end wall 15 closely adjacent

the edge of the opening. This wall thus forms a stop shoulder to be engaged by the end of the thermostat to retain the support or cigarette holder 19 in an otherwise unbalanced position. This thermostat therefore acts as a catch to hold the pivoted supporting member 19 in its normal upper or horizontal or unbalanced position, which is the position shown in Figs. 1, 3 and 5, and the lighted cigarette 20 may be placed in it in the usual manner, as indicated in dotted lines, with its lighted end 20a overhanging the inner end of the element 19 and over the tray. If the cigarette is smoked in the usual way this rest or holder holds it the same as any ordinary tray, but should it be forgotten so that the end 20a burns to a position where this lighted part comes adjacent the looped portion 25 of the bimetal thermostat 23, it will heat this thermostat, causing the free end 28 to shift laterally into alignment with the opening 16, as indicated by the dotted lines 28a in Fig. 1. Therefore, this end no longer engages the inner surface of the end wall 15, but as it is in alignment with the opening 16 it can pass through this opening and permit the inner end of the cigarette support 19 to drop to the inclined position shown in Fig. 4 under the weight of the overbalanced end of the support. This, of course, will dump the lighted cigarette into the tray 10, as shown in dotted lines in Fig. 4. This prevents the cigarette from burning to a position where it could drop on the outside of the tray and onto a table top or other article, to burn or mar it. The device may be reset to the normal position of Figs. 1, 2, 3 and 5 when the thermostat has cooled, by merely swinging the trough or rest 19 to the horizontal position when the free end 28 will again spring to one side of the opening 16 and engage the inner surface of end wall 15 to retain the holder in this position to be again used as a rest or holder for a lighted cigarette. As, however, only relatively slight heating of the thermostat is required to shift its free end 28 from the holding to the released position, the movement required being a very small one, the thermostat cools sufficiently to permit it to swing back to holding position very quickly so that the rest 19 may be reset almost immediately after the cigarette has been deposited in the tray.

It will be noted that the thermostat does not operate to swing the rest to the dumping position, but acts merely as a releasable catch to hold this rest in the normal position, but when heated a relatively small amount is required to shift laterally only a relatively short distance to permit the rest to tip under the action of gravity to deposit the lighted cigarette in the tray.

It is preferred that the inner end portion of the concave or trough-shaped member 19 be provided with a series of small perforations 29, which serve as ventilating openings and prevent accumulation of condensation or moisture to wet the end of the cigarette. They also permit heat to pass through to the thermostat to further insure the heating of this thermostat and therefore increase the reliability of the device and to insure its dumping should the cigarette burn to a position adjacent the thermostat, and also give a more rapid release of this rest at this time.

The bracket 13 may be bent from a flat blank 30 as shown in Fig. 6, stamped from sheet metal. The side arm portions 14 can be bent laterally to the parallel spaced positions shown in the other figures and the mounting lug 17 bent later-

ally from the lower edge of end wall 15 which is the central portion of the blank 30.

It will be seen this device is a very simple one involving a small number of parts, and therefore may be manufactured at low cost. It will also be apparent the device, in view of the location of the curve of the thermostat immediately under the cigarette resting in the support, will be very reliable and can be depended upon to always operate to deposit the lighted cigarette in the tray should it burn to a point adjacent this curved portion.

It is to be understood that although the device has been described as primarily for use with cigarettes, it is equally adapted for cigars and the like, and the term "cigarette" is used in a generic sense to include these articles.

Having thus set forth the nature of my invention, I claim:

- 20 1. In a device of the character described a holder for supporting a lighted cigarette and the like, means for mounting said holder in an unbalanced position, a catch means for retaining the holder in this position including a thermosensitive element associated with said holder in position to be heated by the lighted end of a cigarette on the holder, and said element being movable when so heated to release the holder to permit the holder to tip from said position.
- 30 2. A holder for lighted cigarettes and the like, means mounting said holder in an unbalanced position so that it tends to tip to discharge a cigarette therefrom, and catch means for retaining the holder in said unbalanced position comprising a thermosensitive means positioned to be responsive to heat from the lighted end of a cigarette on the holder and movable when so heated to release the holder to permit it to tip from said position.
- 40 3. A smoker's ash tray, comprising a container for receiving ashes from a burning cigarette, a holder for a cigarette, means mounting the holder in an unbalanced position on the container so that it tends to tip from this position to deposit the cigarette into the container, and a releasable catch means for retaining the holder in this position including a thermosensitive means associated with the holder in position to be affected by heat from the lighted end of a cigarette on the holder and movable when so affected to release the holder and permit it to tip from said position.
- 50 4. A smoker's ash tray, comprising a container for receiving ashes from a burning cigarette, a holder for a cigarette, means mounting the holder in an unbalanced position on the container so that one end tends to drop from this position and the latter end extends over the container, a stationary stop shoulder, a thermosensitive element mounted on the holder in position to be affected by heat from the lighted end of a cigarette on the holder and engaging said shoulder to retain the holder in the unbalanced position, and said element being movable from said shoulder when so affected to release the holder.
- 60 5. A smoker's ash tray comprising a container for receiving ashes from a burning cigarette, holding means for a lighted cigarette comprising a bracket including laterally spaced upright side walls and a connecting end wall provided with an opening, means mounting the bracket on the container, a rest for a lighted cigarette pivotally mounted between said side walls in an unbalanced position so that its inner end extends over the container and tends to drop to deposit a cigarette

on the rest into the container, a thermostatic element mounted on the rest with a portion adjacent the inner end of the rest in position to be affected by the lighted end of a cigarette on the rest and at its free end engaging the said end wall at one side of the opening to retain the rest in this position, and said free end being movable under the effect of heat from said cigarette to shift said end from the wall into alignment with the opening to release the rest and permit the inner end to drop and deposit the cigarette in the container.

6. A smoker's ash tray comprising a container for receiving ashes from a burning cigarette, holding means for a lighted cigarette comprising a bracket including laterally spaced upright side walls and a connecting end wall provided with an opening therethrough, means mounting the bracket on the container, a trough shaped holder for a lighted cigarette pivotally mounted between the side walls in an unbalanced position so that its inner end tends to drop to deposit a lighted cigarette in the holder into the container, a bimetallic thermostat connected at one end to the holder and including a curved intermediate portion adjacent the inner end of the holder in position to be responsive to heat from the lighted end of a cigarette in the holder, and the other end of the thermostat engaging the end wall at one side of the opening to retain the holder in the unbalanced position and movable by heating of said curved portion into alignment with the opening to permit the inner end of the holder to drop to deposit the cigarette in the container.

7. A smoker's ash tray comprising a container for receiving ashes from a burning cigarette, holding means for a lighted cigarette comprising a trough shaped holder for the cigarette pivotally mounted in an unbalanced position with its inner end tending to drop to deposit a lighted cigarette on the holder into the container, a wall forming a stop shoulder, a bimetallic thermostat secured at one end to the holder and including a curved intermediate portion located adjacent the inner end of the holder in position to be responsive to heat from the lighted end of a cigarette in the holder, and the other end of the thermostat normally engaging said shoulder to retain the holder in the unbalanced position and movable from said shoulder by heating of said curved portion to release the holder and permit it to drop to deposit the cigarette thereon in the container.

8. An ash tray comprising a container to receive ashes from a burning cigarette, a trough shaped holder for a lighted cigarette pivotally mounted in an unbalanced position with its inner end tending to drop to deposit a lighted cigarette on the holder into the container, a bimetallic thermostat secured to the holder in position to be responsive to heat from the lighted end of a cigarette in the holder, a stop shoulder, and said thermostat being provided with means normally engaging the stop shoulder to retain the holder in the unbalanced position and movable from said stop shoulder by heating of the thermostat from said cigarette to release the holder and permit it to drop to deposit the cigarette in the container.

9. An ash tray comprising a container to receive ashes from a burning cigarette, a trough shaped holder for a lighted cigarette pivotally mounted in an unbalanced position with its inner

end tending to drop to deposit a lighted cigarette on the holder into the container, a bimetallic thermostat secured to the holder and including a curved portion adjacent the inner end of the holder in position to be responsive to heat from the lighted end of a cigarette resting in the holder, a stop shoulder, and said thermostat being also provided with means to normally engage the stop shoulder to retain the holder in the unbalanced position and movable from said shoulder when said curved portion is heated by a lighted cigarette to release the holder and permit it to drop to deposit the cigarette in the container.

10. In a device of the character described, a trough shaped holder for supporting a lighted cigarette resting therein and provided with a series of perforations therein adjacent one end, means pivotally mounting said holder in an unbalanced position with said perforated end portion tending to drop, a catch means normally retaining said holder in the unbalanced position and including a thermosensitive element located adjacent said perforated end in position to be responsive to heat from the lighted end of a cigarette resting in the holder, and said element being movable by heat from said cigarette to release the catch means to permit said perforated end to drop.

11. An ash tray comprising a container to receive ashes from a burning cigarette, a trough shaped holder for a lighted cigarette provided with a series of perforations at one end, means pivotally mounting said holder in an unbalanced position with the perforated end tending to drop to deposit a cigarette resting in the holder in the container, a bimetallic thermostat secured to the holder and provided with an intermediate curved portion located adjacent said perforated end in position to be responsive to heat from the lighted end of a cigarette resting in the holder, a stop shoulder, and said thermostat being provided with means normally engaging the stop shoulder to retain the holder in the unbalanced position and movable from said stop shoulder by heating of said curved portion to release the holder and permit its perforated end to drop.

12. A holder for burning cigarettes comprising a fixed standard, a cigarette rest plate of trough-like form for containing a lighted cigarette therein, pivotable on the standard and adapted to swing from a horizontal, cigarette-holding position to a downwardly inclined position to dump the cigarette endwise therefrom, and a thermostatic, bi-metal strip attached at one end to the rest plate extending across one end thereof and to supportingly engage with the standard to normally hold the rest plate in said horizontal position, and adapted to be actuated by heat from the burning cigarette to be disengaged from said standard and permit the rest plate to drop to a downwardly inclined position.
